UNITED STATES PATENT OFFICE.

IRA L. FRENCH, OF CHICAGO, ILLINOIS, ASSIGNOR TO THE MANTLE LAMP COMPANY OF AMERICA, OF CHICAGO, ILLINOIS, A CORPORATION OF ILLINOIS.

DESIGN FOR A WALL-BRACKET.

50,099.

Specification for Design.

Patented Dec. 26, 1916.

Application filed September 27, 1916. Serial No. 122,567. Term of patent 14 years.

To all whom it may concern:

Be it known that I, IRA L. FRENCH, a citizen of the United States, resident of Chicago, in the county of Cook and State of Illinois, have invented a new, original, and ornamental Design for a Wall-Bracket, of which the following is a specification, reference being had to the accompanying drawing, forming a part thereof.

In the drawing: Figure 1 is a plan view showing my new design for a wall bracket

for holding lamps. Fig. 2 is a front elevation of the wall bracket, and Fig. 3 is a front elevation of the wall plate for the bracket.

I claim:

The ornamental design for a wall bracket, as shown.

IRA L. FRENCH.

Witnesses:

C. W. DAVIS,

ADOLPH JOHNSON.
